Primary Examiner—Celia Murphy[57] **CLAIM**

The ornamental design for an eyeglass case, as shown and described.

DESCRIPTION

FIG. 1 is a front top perspective view of an eyeglass case showing my new design;
 FIG. 2 is a rear perspective view thereof;
 FIG. 3 is a front elevational view thereof;
 FIG. 4 is a rear elevational view thereof;
 FIG. 5 is a right side elevational view thereof, the left side being a mirror image;
 FIG. 6 is a top plan view thereof; and,
 FIG. 7 is a bottom plan view thereof.
